SKEIN CONVEYER

Alpheus O. Hurxthal, Philadelphia, Pa., assignor
to Proctor & Schwartz, Incorporated, Phila-
delphia, Pa., a corporation of Pennsylvania

Application February 27, 1934, Serial No. 713,217

15 Claims. (Cl. 198—189)

This invention relates to conveyers for materials which are capable of being hung on horizontally disposed poles, such as skeins of yarn, or bunches of tobacco, etc., wherein the opposite ends of the poles are respectively supported by laterally spaced carriers, such as link belts or chains, which advance the poles along a predetermined substantially horizontal course at a definite rate of speed in spaced relation to each other, with the material hanging freely from the poles between the carriers.

Prior to the present invention it has been common practice to support the ends of the poles on the upper runs of endless chains operating solely and disposed entirely in vertical planes respectively; and to provide fixed guards along the opposite sides of the path traveled by the poles, below the carrying runs of the chains, to prevent the material from swaying laterally, engaging and/or becoming entangled with or in the return runs of the carrier belts or with objects disposed along the course of movement of the poles.

This practice in order to avoid chafing and soiling of the material by contact with the fixed guards, despite the precaution taken to make the surface of the guards as smooth as possible necessitated the placing of some kinds of materials, such as fine silk yarns, at a considerable distance inwardly from the opposite ends of the poles to prevent the above mentioned injuries to the material by rubbing against the fixed guards, consequently, in apparatus employed for processing or conditioning the yarn skeins, etc., such as driers, the material, by reason of its being hung a distance from the guards, leaves considerable space at each side of the course of travel of the bulk of material from end to end of the drier through which large quantities of the drying air pass without doing any useful drying of the material and due to the high velocity at which the air travels through these spaces it causes tangling of the yarn nearest the spaces and causes those particular portions of the bulk supported on the conveyer to dry out more rapidly than those portions supported by, at, and near the centers of the holes.

In the case of tobacco, as the leaves in the bunches adjacent the guards dry out, during passage through the drier, contact thereof with the fixed guards causes the leaves or portions thereof to crumble and be lost in the drier.

The object of the present invention is to provide guards which, instead of being fixed along the sides of the course traveled by the conveyer, will travel concurrently with the side chains re-

spectively, to avoid relative movement between the guards and the material supported by the poles and hanging therefrom in the space between the synchronously moving side guards.

One extremely valuable advantage of this invention resides in the adaptability of the poles to being loaded to the point where the material supported thereby lies immediately adjacent and in contact with the traveling guards by reason of there being no relative movement between the guards and the material as they simultaneously travel through the drier, thus effecting a considerable saving in drying air, or the putting into useful service of air otherwise wasted, by reason of the above noted air passages being blocked by the material lying at, near, and against the guards.

Another advantage of the invention resides by reason of it being possible to load the poles to full capacity, in increasing the hourly capacity of the drier as a whole.

Another advantage accruing to the present invention is the elimination of the chafing, soiling, entangling, or crumpling of the material by contact with a relatively movable object while being conveyed through the drier.

Another object of the invention is to run the carrier chains solely in horizontal planes whereby, instead of the return runs of the endless chains moving in opposite directions at or near the traveling guards to rub against and injure the guards and the material lying against the guards, these return runs are maintained at all times in the same horizontal plane with the runs on which the poles are carried and consequently cannot injure neither the traveling guards nor the material adjacent thereto.

In the preferred form of the invention each of the traveling guards at the opposite sides respectively of the course comprises flexible endless aprons having an upper longitudinal edge secured to or supported adjacent each pole carrier and driven in a manner to travel at the same rate of speed as the carrier, with the body of the flexible apron hanging downwardly and freely to protect the material as it travels through its prescribed course.

In a modified form of the invention the traveling guard may be formed in sections respectively secured at their upper ends to one or more of the links of the pole-carrying chains and the guard proper may be composed of either flexible material or relatively stiff material with the edges of successive guard sections in abutting or over-

lapping relation to each other longitudinally of the course.

In the accompanying drawings:

Fig. 1 is a perspective view of a portion of one of the pole carriers with a guard partly secured to the carrier and partly released from the carrier;

Fig. 2 is a fragmentary plan view showing the guard secured to the carrier;

Fig. 3 is a side elevation of the carrier with the guard removed;

Fig. 4 is a transverse sectional elevation taken on the line 4—4, Fig. 2;

Fig. 5 is a side elevation diagrammatically illustrating a drier equipped with traveling guards in accordance with the present invention;

Fig. 6 is a transverse sectional elevation taken on the line 6—6, Fig. 5;

Fig. 7 is a side elevation of a carrier and a sectional guard depending therefrom; and

Figs. 8 and 9 illustrate a modification of the invention.

As shown in Figs. 1 to 4 inclusive, the pole carriers in the present instance, each consists of a continuous endless belt or chain 1 composed of a series of links 2, 2 connected, one to the other, through and by vertically disposed pins or pintles 3, 3, for relative pivotal movement confined solely to a horizontal plane.

Each link 2, or a predetermined link in a group thereof, is provided with a wheel 4 which is rotatably mounted on a horizontally disposed axle 5, pinned or otherwise secured in the link against longitudinal and/or rotary movement relative thereto.

The chains 1, 1 are spaced apart laterally, as shown in Fig. 6, and pass around a pair of sprocket wheels 6 and 7, which are spaced apart and disposed in a common horizontal plane at the opposite ends respectively of the course traveled by the pole-carrying and return runs 1a, 1a and 1b, 1b respectively of the endless chains 1, 1, and adapted for rotation in said horizontal plane about vertical axes provided by shafts 8 and 9, as shown in Fig. 5.

The shafts 8 and 9 may be driven in unison by any desired means, such, for example, as from and by a transversely extending shaft 10 through chain and sprocket mechanism 11—12—13, the sprocket 13 being secured to a short shaft 14 to which is fixed a gear 15 meshing with a gear 16 on the lower end of the shaft 9, in each instance.

The links 2, 2 are each provided with a socket or sockets 17 for the reception of the ends of the poles x, x on which the material y is hung.

The traveling guard, in the preferred form of the invention, comprises a continuous endless belt 20 composed of any suitable material preferably a flexible textile material such as duck. The belt 20 passes around drums or wide faced pulleys 21 and 22 mounted on the shafts 8 and 9 respectively below the sprockets 6 and 7 around which the carriers 1, 1, pass.

The upper edge of the flexible guard belt 20 preferably extends upwardly to and in a plane immediately adjacent the links 2, 2 of the chains 1, 1 to a plane approximately in line with the bases of the pole sockets 17, while the lower edge of the guard is preferably disposed below the lowest plane assumed by the longest units of material y supported by the poles x.

The pitch diameters of the sprockets 6 and 7 and the effective diameters of the drums 21 and 22 are so related that the chains 1 and the guards 20 travel at the same linear speed.

In order to maintain the above relationship between the carriers and the guards it is preferable to secure the upper edge of the flexible belts or aprons 20, 20 to the carrier chains 1, 1 respectively and for this purpose each, or any desired number of the axles for the wheels 4 are extended beyond the chains 1, 1 at one side thereof, as indicated at 5a, see Figs. 1 to 4. Each extension 5a is circumferentially grooved as at 23, to receive the upper edge 24 of a horizontal slot 25 formed in a hanger plate 26 secured to the apron 20 in any suitable manner, as by rivets 27.

The horizontal slot 25 is provided with a right angle opening 28 of sufficient size to permit the extension 5a to enter to a depth to allow the edge 24 of the horizontal slot 25 to seat itself in the groove 23 for supporting the guard 20 from and by the carrier chain 1.

While one specific way of attaching the guard 20 to the carrier 1 has been illustrated other forms of attaching means may be provided without departing from the spirit of the invention.

In order to off-set any tendency of the carrier chains 1 to tilt inwardly toward each other under the weight of the poles, the material on the poles and the guards, each or any desired number of the wheel axles 5 may be extended beyond the chains 1, 1, at the opposite sides of the links 2 from which the extensions 5a project, as indicated at 5b in Figs. 2 and 4, for the reception of rollers 30 which are adapted to bear against the underside of a rail 31 which extends substantially parallel to the rail 32 on which the supporting wheels 4, 4 for the chains 1, 1 run.

The rails 31 and 32 preferably extend the full distance between the sprockets 6 and 7 to prevent sagging and tilting of the chains and the guards.

In some instances, as shown in Fig. 7, the guard may be made in a plurality of sections 20a respectively carried by the links 2a with the vertical edges of the sections in laterally abutting or overlapping relation to each other and in place of these sections being composed of duck or other flexible material they may be composed of some relatively stiff material such as sheet fiber or metal.

In some instances, as shown for example in Figs. 8 and 9, the carrier chains 1c may be disposed in vertical planes while the guards 20c are disposed in horizontal planes and the two may be synchronized as to linear travel in any suitable manner as for example by spiral gears 35 and 36 secured to the shafts 8c and 37 to which the drum 21c and sprocket 6c are respectively secured.

In such a case the guard 20c may be prevented from working its way downwardly on the drum 21c by any suitable means such as by having a perforated flexible strip 38 secured to the upper edge of the guard and running around a wheel 21d of the same diameter as the drum 21c with pins or teeth 39 on the periphery of the wheel 21d extending into the perforations of the flexible strip 38.

In such a case as shown in Figs. 8 and 9 the return runs of the carrier chains 1c would be disposed wholly within the guard belt 20c protecting the material on the poles against contact with the return runs of the carrier chains.

I claim:

1. The combination of a pair of laterally spaced horizontally movable carriers adapted to support the opposite ends respectively of each of a series of poles having material freely suspended therefrom intermediate said carriers, and

a pair of guards adapted to travel concurrently with said carriers respectively intermediate the plane of the poles and the lowermost portions of the freely hanging material for lateral confining engagement with the freely hanging portions of the material disposed on the poles adjacent said carriers.

2. The combination of a pair of laterally spaced horizontally movable carriers adapted to support the opposite ends respectively of each of a series of poles having material suspended therefrom intermediate said carriers, and guards depending respectively from and adapted to travel concurrently with the carriers for engagement with depending portions of the material disposed on the poles adjacent the carriers.

3. The combination of a pair of laterally spaced horizontally movable carriers adapted to support the opposite ends respectively of each of a series of poles having material suspended therefrom intermediate said carriers, and guards depending respectively from and adapted to travel concurrently with the carriers between the carriers and the material for engagement with depending portions of the material disposed on the poles adjacent the carriers.

4. The combination of a pair of laterally spaced horizontally movable carriers adapted to support the opposite ends respectively of each of a series of poles having material freely suspended therefrom intermediate said carriers, a pair of guards adapted to travel concurrently with said carriers respectively intermediate the plane of the poles and the lowermost portions of the freely hanging material for lateral confining engagement with the freely hanging portions of the material disposed on the poles adjacent said carriers, and means for synchronously actuating said carriers and guards to effect said concurrent movement thereof.

5. The combination of a pair of laterally spaced horizontally movable carriers adapted to support the opposite ends respectively of each of a series of poles having material freely suspended therefrom intermediate said carriers, a pair of guards adapted to travel concurrently with said carriers respectively intermediate the plane of the poles and the lowermost portions of the freely hanging material for lateral confining engagement with the freely hanging portions of the material disposed on the poles adjacent said carriers, and means forming a driving connection between the guards and the carriers for effecting said concurrent movement thereof.

6. The combination of a pair of laterally spaced horizontally movable carriers adapted to support the opposite ends respectively of each of a series of poles having material suspended therefrom intermediate said carriers, guards disposed below and adapted to travel concurrently with said carriers respectively for engagement with depending portions of the material disposed on the poles adjacent said carriers, and means securing the guards to the carriers for supporting the guards and effecting said concurrent movement between the guards and the carriers.

7. The combination of a pair of laterally spaced horizontally movable carriers adapted to support the opposite ends respectively of each of a series of poles having material suspended therefrom intermediate said carriers, an endless guard belt traveling in a horizontal plane around each carrier and depending from the carrier to engage depending portions of the material carried

by the poles adjacent the carriers, and means for synchronously actuating said guard belts and said carriers to effect concurrent movement thereof.

8. The combination of a pair of endless carrier belts disposed substantially in a common horizontal plane in substantially parallel laterally spaced relation to each other with the innermost runs of said carrier belts arranged to support the opposite ends respectively of each of a series of poles having material suspended therefrom between the pole-carrying runs of said carrier belts, and a pair of endless guard belts substantially coinciding with and depending from said carrier belts respectively and adapted to operate concurrently with said carrier belts for engagement with depending portions of the material supported by the poles adjacent the carrier belts.

9. The combination of a pair of endless carrier belts disposed substantially in a common horizontal plane in substantially parallel laterally spaced relation to each other with the innermost runs of said carrier belts arranged to support the opposite ends respectively of each of a series of poles having material suspended therefrom between the pole-carrying runs of said carrier belts, a pair of endless guard belts substantially coinciding with and depending from said carrier belts respectively and adapted to operate concurrently with said carrier belts for engagement with depending portions of the material supported by the poles adjacent the carrier belts, and means for synchronizing the actuations of said belts.

10. The combination of a pair of endless carrier belts disposed substantially in a common horizontal plane in substantially parallel laterally spaced relation to each other with the innermost runs of said carrier belts arranged to support the opposite ends respectively of each of a series of poles having material suspended therefrom between the pole-carrying runs of said carrier belts, a pair of endless guard belts substantially coinciding with and depending from said carrier belts respectively and adapted to operate concurrently with said carrier belts for engagement with depending portions of the material supported by the poles adjacent the carrier belts, and means forming a driving connection between said belts to effect said concurrent movements thereof.

11. The combination of a pair of endless carrier belts disposed substantially in a common horizontal plane in substantially parallel laterally spaced relation to each other with the innermost runs of said carrier belts arranged to support the opposite ends respectively of each of a series of poles having material suspended therefrom between the pole-carrying runs of said carrier belts, a pair of endless guard belts substantially coinciding with and depending from said carrier belts respectively and adapted to operate concurrently with said carrier belts for engagement with depending portions of the material supported by the poles adjacent the carrier belts, and means securing the guard belts to the carrier belts for effecting said concurrent movements thereof.

12. The combination of a pair of endless carrier belts disposed substantially in a common horizontal plane in substantially parallel laterally spaced relation to each other with the innermost runs of said carrier belts arranged to support the opposite ends respectively of each of a

series of poles having material suspended therefrom between the pole-carrying runs of said carrier belts, a pair of endless guard belts substantially coinciding with and depending from said carrier belts respectively and adapted to operate concurrently with said carrier belts for engagement with depending portions of the material supported by the poles adjacent the carrier belts, and means detachably securing the guard belts to the carrier belts for effecting said concurrent movements thereof and for readily removing the guard belts from the carrier belts.

13. The combination of a pair of endless carrier belts disposed substantially in a common horizontal plane in substantially parallel laterally spaced relation to each other with the innermost runs of said carrier belts arranged to support the opposite ends respectively of each of a series of poles having material suspended therefrom between the pole-carrying runs of said carrier belts, a pair of endless flexible guard belts substantially coinciding with and depending from said carrier belts respectively and adapted to operate concurrently with said carrier belts for engagement with depending portions of the ma-

terial supported by the poles adjacent the carrier belts, and means detachably securing the guard belts to the carrier belts for effecting said concurrent movements thereof and for readily removing the guard belts from the carrier belts. 5

14. An endless flexible guard belt arranged to travel in a horizontal plane about relatively spaced vertically arranged axes, attachments secured to the belt adjacent the upper edge thereof for supporting the belt during said travel, and a drive belt adjacent and arranged to travel concurrently with the upper edge of the guard belt, and means on the drive belt engaging the attachments on the guard belt and providing a driving connection between said belts. 10

15. An endless flexible guard belt arranged to travel in a horizontal plane about relatively spaced vertically arranged axes, a drive belt adjacent and arranged to travel concurrently with the upper edge of the guard belt, and pins on one of said belts projecting into openings formed in the other of said belts for providing a readily detachable positive driving connection between said belts. 20
